UNITED STATES PATENT OFFICE.

WILLIAM H. LUTHER, OF GLASGOW, SCOTLAND.

SHEARING-MACHINE.

1,024,409.

Specification of Letters Patent.

Patented Apr. 23, 1912.

Application filed December 14, 1910. Serial No. 597,254.

To all whom it may concern:

Be it known that I, WILLIAM HENRI LUTHER, a subject of the King of Great Britain and Ireland, residing at Petershill Road, 5 Glasgow, Scotland, manufacturer, have invented a new and useful Shearing-Machine, of which the following is a specification.

This invention has reference to improvements in and relating to machines for treating sheet metal plates and the like, and essentially consists in constructing and arranging the parts of a machine that will automatically shear or trim simultaneously both edges of a metal sheet, although it can 10 be adapted to trim only one of such edges; and can also be applied for cutting the sheets, or for beading, molding, or similarly treating either or both edges of the metal sheet, and which will be more accurate and 15 efficient in action and effect an economy in cost of treating the material not hitherto obtained.

In order that others skilled in the art to which my invention relates may be able to 20 properly understand same I have hereunto appended two sheets of explanatory drawings in which—

Figures 1, 2 and 3 are respectively an end elevation, a side elevation at right 25 angles thereto and a plan view of a machine, as constructed according to my improvements, for treating sheet metal plates and the like.

Referring to these drawings:—According 30 to my improvements a sheet plate of iron, steel, or the like, or a series of such sheet plates is or are placed over a pair of parallel guiding rails *a*, and this sheet or sheets is or are held down in horizontal position on 35 the rails *a* by the action of an electro-magnet, or preferably and as shown a series of electro-magnets *b* located longitudinally under and along the center of the sheet, but which may be placed near the edge or other 40 parts of the sheet to keep same in position. Two parallel girders *c* of any suitable cross section are arranged on a suitable bed plate *d* at spaced distances apart, and either or 45 both girders are by screw, rack or other gear *e* made adjustable toward each other to suit the sizes of the plates to be treated.

A traveling frame or crosshead *f* is mounted on each of these parallel girders *c*, and cutting tools *g*, *g*¹, are mounted in housings *h* on each of these frames *f*, the tools

preferably consisting each of a pair of edge cutting revolving rolls *g*, *g*¹, and these frames *f* receive a reciprocating or traveling motion through rack and pinion or equivalent gear *i*, while the rolls simultaneously receive a rotating motion through wheel or other gearing *j* driven from an electro-motor or other prime moving force, so that the plate held in horizontal position by the electro-magnets *b* has its edges 60 sheared or trimmed off to the desired degree.

The operation of the machine is as follows:—A sheet-metal plate is placed in position on the rails *a* and is securely 70 held there by the electro-magnets *b*. The traveling frames *f* are in the position shown by Fig. 3 and are traveled to the other end of the machine by the rack and pinion gearing *i* as the tools *g*, *g*¹, are rotated by the gearing *j* so that the edges of the sheet are trimmed. When the frames *f* reach the end of their travel the motion is reversed so that they travel backward to be ready to trim the next sheet. While the 75 frames *f* are traveling backward the electro-magnets *b* are demagnetized and so disconnected from the sheet which is pulled out of the machine along the rails *a* by hand from the end *A* and a new sheet is inserted from 80 the end *B*. Instead of pulling the trimmed sheet out of the machine by hand this operation may be accomplished automatically by fitting hooks or “dogs” *k* to brackets *l* secured to frames *f*. While the frames *f* are 85 traveling forward the points of the hooks *k* travel along the top of the sheet being trimmed and on reaching the end of the sheet they will fall over so that when the frames *f* are traveled backward they will 90 pull the sheet out of the machine at the end *A*. In the case of copper, zinc, or other 95 non-magnetic substances, these sheets may be held down on their supporting rails by an iron or steel sheet or plate on which the 100 electro-magnets would act.

Instead of revolving cutters other tools with suitable gearing may be substituted on the traveling frames for giving a beaded, molded, or like action to the edges of the sheet metal plates. If desired the electro-motor can be started and stopped by a controller which may be operated by push-buttons located at different parts of the machine.

What I do claim as my invention and desire to secure by Letters Patent, is:—

1. The combination in a machine for operating simultaneously on the two edges of a sheet, of a bed plate; two elongated structures thereon; means for adjusting said structures toward and from each other; housings respectively mounted on said structures; means for simultaneously moving said 10 housings on the structures parallel to each other; a tool carried by each of the housings; and fixed means for holding the sheet stationary while said housings with their tools move along its opposite sides and operate thereon.
2. The combination in a machine for operating simultaneously on the two edges of a sheet, of a bed plate; two elongated structures thereon; means for adjusting said structures toward and from each other; housings respectively mounted on said structures; means for simultaneously moving said housings on the structures parallel to each other; a tool carried by each of the housings; means 20 for simultaneously driving said tools from the same source of power; and a series of fixed electro-magnets for holding the sheet stationary while the housings with their tools are moved to operate thereon.
3. The combination in a machine for operating simultaneously on the two edges of a sheet, of a bed plate; two elongated structures thereon; means for adjusting said structures toward and from each other; 25 housings respectively mounted on said structures;

tures; means for simultaneously moving said housings on the structures in lines parallel to each other; a tool carried by each of the housings; an elongated, stationary sheet-supporting rail mounted on each of the supporting structures and extending in position to assist in carrying the sheet operated on by the tools; and means for holding the sheet stationary on said rails while the housings and their tools are moved to operate thereon. 45

4. The combination in a machine for operating simultaneously on the two edges of a sheet, of a bed plate; two elongated structures thereon; means for adjusting said structures toward and from each other; 50 housings respectively mounted on said structures; means for simultaneously moving said housings on the structures parallel to each other; a tool carried by each of the housings; a sheet-supporting rail mounted on each of the supporting structures and extending in position to assist in carrying the sheet; means for holding the sheet stationary while it is being operated on by the tools; with a sheet-engaging device on each of the 55 housings for moving the said sheet after it has been operated on.

In testimony whereof I have signed my name to this specification, in the presence of two subscribing witnesses.

W. H. LUTHER.
